UNITED STATES PATENT OFFICE

168,074

BRACKET OR THE LIKE

Thomas R. Symington, Baltimore, Md.

Application January 11, 1949, Serial No. 185

Term of patent 14 years

(Cl. D33—3)

To all whom it may concern:

Be it known that I, Thomas R. Symington, a citizen of the United States, residing at Baltimore, in the county of Baltimore and State of Maryland, have invented a new, original, and ornamental Design for Bracket or the like, of which the following is a specification, reference being had to the accompanying drawing, forming part thereof.

The figure shown on the drawing is a perspective view of a bracket or the like, showing my new design.

I claim:

The ornamental design for a bracket or the like, substantially as shown.

THOMAS R. SYMINGTON.
